Primary Examiner — Holly Baynham*Assistant Examiner* — Rhea Shields(74) *Attorney, Agent, or Firm* — WPAT, P.C.; Anthony King(57) **CLAIM**

The ornamental design for a multi-direction socket, as shown and described.

DESCRIPTION

FIG. 1 is a perspective view of a multi-direction socket showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof.

FIG. 8 is another perspective view thereof; and,

FIG. 9 is another perspective view thereof.
